UNITED STATES PATENT OFFICE.

WILLIAM C. EDWARDS, JR., OF KANSAS CITY, MISSOURI.

REINFORCED CONCRETE STRUCTURE.

1,013,592.

Specification of Letters Patent.

Patented Jan. 2, 1912.

Application filed January 17, 1911. Serial No. 603,172.

To all whom it may concern:

Be it known that I, WILLIAM C. EDWARDS, Jr., a citizen of the United States of America, residing at Kansas City, in the county of Jackson and State of Missouri, have invented certain new and useful Improvements in Reinforced Concrete Structures; and I do hereby declare that the following is a full, clear, and exact description 10 of the invention, reference being had to the accompanying drawings, forming a part of this specification.

The invention relates to reinforced concrete structures, such as walls for buildings, 15 and the various other well known applications of reinforcement in which the reinforcement is primarily an embodiment of a structural form for the concreting material, and it has for its object: First: A means of 20 combining structural parts of a form and reinforcement of the character described, with a standard positioning of the studs. Second: A moisture-resisting, hollow concrete wall. Third: To reinforce lines of 25 separation on the joints of the reinforcement and form. Fourth: In hollow wall construction, to obtain a bond between the walls in courses and support the plastic material in arch formation. Fifth: To pro- 30 vide ribs for the spacing plates of the form between the studs and inter-lock opposite parts of the ribs with each other. Sixth: To afford a reinforcement with opposite, 35 ribbed formation plates. Seventh: To pro- vide a universal support at the corners of concrete structures.

The invention consists in the novel construction and combination of parts, such as will be first fully described and then specifically pointed out in the claims.

In the drawings: Figure 1. is a view, in perspective, of portions of concrete walls at the angle formed of side walls, of a building, and of a partition wall, portions of the respective walls being broken away to show the invention. Figs. 2, 3 and 4 are detail, 45 isometric views of the respective parts of a combined form and reinforcement, of the hollow wall construction, as seen in Fig. 1, and Fig. 5. is an isometric view of the parts as seen in Figs. 2, 3 and 4 assembled together and in a position to receive the concreting material. Fig. 3^a is a detail, vertical, 50 sectional view on line α , α , in Fig. 6. Fig. 6. is an enlarged, plan view of the parts of the completed form as seen in Fig. 5. Fig. 7.

is a plan view of the assemblage of modified parts. Fig. 8. is a plan view, enlarged, of the combined form and reinforcement, as seen in the partition wall in Fig. 1. Fig. 9. 60 is an isometric view, enlarged (a broken portion), of the bed plate for the side walls of the structure. Fig. 9^a is a similar view of a bed plate construction for partition walls, as seen in Fig. 1. Fig. 10. is an isometric view of a broken portion of the bridging in the side walls, as seen in Fig. 1. Fig. 10^a is a similar view of a bridging construction for partition walls, as seen in Fig. 1. Fig. 11. is a view, in perspective, of the support for the spacing members of the reinforcement at the corners of the walls. Fig. 12. is an enlarged, detail view of the vertical support and reinforcement for the abutting ends of the spacing plates in the partition 75 wall, as seen in Fig. 1. Fig. 13. is a side view of the reinforcing link to the ribs in the spacing members of the combined form and reinforcement. Fig. 14. is an isometric view, on an enlarged scale, of one continuous body portion of the reinforcement, showing a modification of the studs, as seen in Fig. 2. Fig. 15. is a plan view of a plurality of the body sections, as seen in Fig. 14, assembled together to constitute the combined form and reinforcement. Fig. 16. is an isometric view of a modification of the construction of the body-section, as seen in Fig. 1, and Fig. 17. is a plan view of a plurality of entrained body-sections assembled 80 together, to constitute a combined form and reinforcement of the body section, as seen in Fig. 16. Fig. 18. is a plan view of an assemblage of the body section seen in Fig. 14, and the body-section seen in Fig. 16, to 85 form an alternate alinement of studs to that seen in Fig. 1. Fig. 19. is a view in perspective, of a modification of the cross-tie reinforcement seen in the bed plate in Fig. 9. 90

Similar numerals of reference indicate 100 corresponding parts in all the figures of the drawing.

In the construction of the invention, particularly for the erection of concrete walls of buildings and like structures, the composite forms employed for holding the wet concrete, and which also become the reinforcement are dissimilar as in respect to the monolithic, single wall and hollow wall construction, as illustrated.

105 In the hollow wall construction, which will be first described, a complete reinforce-

ment for the erection of a hollow wall in courses is seen in Fig. 5, which is an embodiment of the independent body-sections shown in Figs. 2, 3 and 4, and these may be 5 designated for convenience, main and allied body-sections, respectively, of a complete form and reinforcement. The main body portion, as seen in Fig. 2, consists of a longitudinally-extended plate, such as sheet 10 steel, of such thickness as to be readily bent, and of the requisite length and width. A short portion of this main body plate, intermediate its ends, is bent transversely to the plate, to form a distance piece 22. Short, 15 outer portions of this distance piece are bent at right angles and in opposite, longitudinal directions, to form offsets 23 and 24, respectively. From the outer portions of these offsets, short portions 25 and 26, of the 20 main portion of the plate, are bent at right angles to the offsets 23 and 24, and extended inwardly, and thence bent at 27 and 28, respectively, and extended in opposite directions in the longitudinal direction of the 25 main body plate the respective offsets with the adjacent parts thereto forming grooves. To the points 30 and 31, respectively, and from said points, the main body plate is again bent at right angles from the points 30 and 31 and portions 32 and 33, of the 30 main plate extended in opposite directions and in transverse direction to the main body plate to the respective points 34 and 35, at which points portions of the main body 35 plate are again bent at right angles and short portions 36 and 37, respectively, extended a short distance in the longitudinal direction of the main body plate to the respective points 38 and 39, at which points 40 portions of the main plate are bent inwardly to form inner vertically grooved depressions or recesses 40 and 41, respectively, the opposite sides of the respective recesses 40 and 41, opposite to the sides formed by the 45 angles 38 and 39, being extended outwardly a slight distance beyond the lines of the surfaces of the longer, bent portions 36 and 37, to the points 42 and 43, respectively, at which points the remaining portions 45 and 50 46, of the main body plate are bent at right angles, the portions of the plate extending in opposite, parallel planes the requisite distance for the purpose, further explained. The portions of the main body plate designated by the previous description and indicated by the reference numerals 23, 32, 36 and 40, constitute one circuitous plate or stud, and the portions 24, 33, 37 and 41 constitute another circuitous plate or stud, 55 separated by the distance plate 22 the recesses within the respective studs formed by the respective bent portions of the distance plate having their openings in opposite directions. From the respective portions 45 and 46, short portions of the plates are bent

inwardly, in the form of loops, and these loops flattened together as at 47, to form stiffening elements or ribs to the plates. In order to resist any separation of the folded portions of the ribs in the opposite side-portions of each one of the ribs, a short distance downwardly from the upper end of the rib are vertical slits 48, penetrating the ribs which intersect horizontal slits 49, leaving rectangular portions 50 and 51, the lower, 70 free ends of which portions are bent from one side of the rib through the openings made by the slits, and folded on the other side of the rib, as seen in Fig. 3^a, thus forming a clamp to the parts of the rib. Other 75 clamps are made in the same manner in the rib and also in the other ribs, as seen in the drawing.

The portions 45 and 46, of the main body plate, constitute spacing plates between 85 studs, whereby a defined standard distance may be obtained and preserved, and especially in hollow wall construction, the position of the studs will in the assemblage of the forms accurately meet the stresses set 90 up in concrete construction. Near the outer end of the portion 45, of the reinforcing body plate, the plate is bent inwardly and folded upon itself and the parts flattened similar in manner to the ribs 47, but shorter 95 in length, as seen at 52, from which point a short portion 53 extends upon the inner surface of the plate 45, a distance slightly greater than the width of the surfaces 36 and 37, of the studs, and is then bent at 100 right angles inwardly and parallel with the ribs 47 and a slight distance beyond the line of the inner surfaces of said ribs, to form the stud 54, the inner portion of which stud is bent at right angles at 55, and a portion 56 extended outwardly a slight distance in excess of the width of the portions 27 and 28, of the studs intermediate the ends of the body-section, and is then bent at 105 57, at right angles and in parallel plane 110 with the portions 54, of the stud, and terminates at 58, a slight distance from said point 57, thereby forming the end stud to the plate, which may be telescoped and interlocked with the stud having like configuration of an allied plate. At the outer end portion of the plate 46 is a similar interlocking stud 59, which is constructed precisely the same as the portions 52, 53, 54, 115 56 and 58, upon the portion 45, of the plate. 120

In the plates 45 and 46 are apertures 58^a, these apertures being formed by vertical slits and intersecting, lower slits, leaving a lip 59^a, the free end of which is bent from the inner side of the plates outwardly and in a horizontal position. These apertures and lips are made in both horizontal and vertical series, so that the flushing of wet concrete within the plates may pass readily through the apertures and at any point along the sur- 125 130

faces of the plates. For the longitudinal extension of the main body-section in the wall, I employ an allied section 60, as seen in Fig. 3. This section consists of a spacing member or plate 61, which is constructed precisely the same as the portion or plate 46, of the main body section. At the end of plate 60 corresponding to that having stud 59 is a stud 62, and at the other end of said

5 plate a recess 63, and stud 64, which is precisely the same as the stud plates 24, 33 37 and 41, in Fig. 2. This section is also provided with a distance plate 65, which is the same as distance plate 22, in Fig. 2, and

10 15 which extends from stud 64 a corresponding distance to an offset 66, which is the same as the offset 23, and with the said offset is connected a short, recessed terminal portion 67, which is the same as the portion 27, of the

20 25 stud in Fig. 2, and a fractional portion of the portion or plate 32 of said stud. This section 60 is also provided with apertures and lips as before described in Fig. 2.

For the purpose of lateral extensions in the walls of the reinforcement and form, and also for so combining these allied sections that the spaces may be made within the form of regular proportions, I employ another section as seen in Fig. 4. This section

30 35 40 45 50 55 60 65 70 75 80 85 90 95 100 105 110 115 120 125 130

70 consists of a longitudinal spacing member or plate 71, similar in construction to the members 45 and 60, in Figs. 2 and 3, respectively, but is shorter in length.

Section 70 is provided at one end with an interlocking stud 72, and at the other end the plate is bent at right angles at 73, and extended the requisite distance from the line of the outer surface of said plate as far as it may be desired to establish the width of spaces within the form and contribute a distance plate 74, this plate at its outer end being bent at right angles and extended a slight distance 75, parallel with plate 71, and a portion 76 is extended inwardly in the direction of plate 71, a short distance, and a portion 77 bent at right angles and extended a short distance parallel with the plate 71. The section 70 is also apertured and provided with the lips as described of the plates in Fig. 2. A continuous form and reinforcement for cement is composed of the main body section and allied sections 60 and 70, as seen in Fig. 5, in the following manner: The stud of a spacing plate 60 is telescoped within the parts 52, 53, 54 and 56, of the stud, on the end of plate 45, of the main body section and within the interlocking stud 62, of the section 60 is telescoped the parts 30, 32 and 36, of another main body section, the plate 45 continuing the length of the outer side of the form, and the part 59, of the interlocking parts of the stud on the outer end of plate 46 is caused to telescope with the parts 66 and 67, of the section 60. Thus combined, the sections

mentioned form a compartment, the studs being opposed to each other, and the length of the form desired being a repetition of the assemblage of parts described, the section shown in Fig. 3 being introduced alternately with the main body section, to form alternate compartments, the formation of the other compartments being as further described.

Another length of the main body section and section 60, are then assembled, as before described, reversed in position to and placed parallel with the former sections, with the open spaces opposite the studs in the other longitudinal sections. An interlocking spacing member or section 70 is then placed opposite the alternate openings, or spaces, in the opposing, interlocked main body sections and section 60, and the interlocking stud 72 telescoped over the parts 26, 31 and 35, of the intermediate inner stud of the main body section, on the inner wall sections, and the parts 74, 76 and 77, on the other end of plate 70 caused to engage with the end rib on plate 46, thus forming compartments with the said allied sections, wherever it is placed in the hollow wall forms. As seen in Figs. 5 and 6, in order that the interlocking part 72 shall interlock with parts of a stud 26, 33 and 37, that these plates 70 must be reversed in position, thus bringing the other parts 74, which space the forms apart, opposite each other, and an opening 78 is formed between, communicating with compartments on opposite sides of the form circuitously, and forming between plates 46 and 70 vertical spaces or shafts 79, as seen in Fig. 6, which are obviously the length of the main body section. The form and reinforcement seen in Fig. 5, as shown on Fig. 1, are positive and negative reproductions on the left and right hand side portions of the hollow wall, respectively.

It will be observed that the surfaces 36 and 37, of the studs in the main body section set back from the line of the outer surfaces of the plates 45 and 46, so that the interlocking parts of other sections are flush therewith, these recesses 40 and 41 preventing any lines of separation with an adjacent section transversely to the forms.

In Fig. 9 is illustrated a preferred form of bed for the initial support of the combined forms and reinforcement, which consist of longitudinally-extended plates 80, 120 which are in excess of the width of the combined form and reinforcement, as seen in Fig. 5. The outer, longitudinal portions of the plate are bent at right angles in an upward direction to form flanges 81. Inner flanges 82 are formed in the central portion of the bed 80, in the following manner: The plate 80 is cut longitudinally at points equidistant from the flanges 81, equal to the length of the shaft opening 79, and between

said lengths are left the transverse connecting portions 83. The parts separated by the longitudinal dividing lines are bent upwardly, forming the flanges 82. The flanges 5 81 and 82 are apertured at 84, and provided with the lips 85, on their outer surfaces, the bottom portion of the bed being provided with apertures 86 only.

A coördinate of the reinforcement consists of a bridging 90, as seen in Fig. 10, and which is also made from a longitudinal strip of metal, of the same width as the plate 80, from which the bed is formed. This bridging consists of the outer sectional side 10 flanges 91, and parallel inner sectional flanges 92, spaced apart a distance corresponding to that between the plates 45 and 70, of the reinforcement seen in Fig. 6. At 15 intervals in bridging 90 and in the inner flanges 92, portions 93 are cut away transversely leaving a broad space, and in which spaces are transverse connecting plates 94, connected at its ends with the inner surfaces of the outer flanges 91, at a point intermediate the upper and lower horizontal 20 surfaces of said flanges. With the inner flanges 92 are connected at an intermediate point between their upper and lower longitudinal surfaces, the inner ends of trans- 25 verse, narrow reinforcing strips 95, which are connected at like points with the inner surfaces of the respective outer flanges 91. With the strips 95 are connected integrally the longitudinal strips 96, extending from 30 one strip to an adjoining strip. It is obvious that the parts of the bridging are 35 integral with the flanges and that these parts may be made from a single sheet of metal and the sectional flanges bent upwardly from the lines of separation.

Another portion of the reinforcement as seen in Fig. 1 consists of a retainer for the parts of the form and reinforcement, as seen in Fig. 11, at the corner of the building 40 structures. This retainer consists of two angle-plates 97 and 98, each angle plate having two parts at right angles to each other, the angle-plates being connected at the apex of the inner angle plate 98, and 45 with the inner surface of the apex of the outer angle plates 97 by the tie plate 99, which in length is sufficient to permit of the entrance between the respective angle-plates of the parts of the combined form and 50 reinforcement, as seen in Fig. 1, and in the manner further described.

It is obvious that the parts 97, 98 and 55 99, of the angle and tie plates may be made from a single sheet of metal plate whose parts terminate at 99^x, as seen in Fig. 11, in the customary manner of bending metal forms.

In Fig. 12, I have shown at 100 a form of reinforcement for joining the partition 60 walls with the main, outer walls of a build-

ing, no change in construction being made from that of the bed plate in Fig. 9^a, except that the lips in flanges are at a different angle from those shown in flanges in Fig. 9^a.

In the erection of the walls of a building, 70 as seen in Fig. 1, a concrete footing 101 is first laid in the ground in the direction in which the walls are to be constructed, upon which footing are laid horizontally the apertured bed-plates 80. At the angle 75 formed by the intersection of side walls the bed plates are cut and fitted to the mitre of said angles. Upon the bed plates 80, between the flanges 81 and 82, are mounted the combined form and reinforcement, as 80 seen in Fig. 5, in such a manner that the spaces 78, between the spacing members 74, of plates 70, are positioned above the transverse connecting plate 83, of the flanged parts of the bed for hollow wall construc- 85 tion.

At the angles formed by the intersection of the sections of reinforcement approaching each other at right angles, as seen in Fig. 1, a mitre cut is made of the parts of 90 the sections, and the parts removed so as to permit a joint to be made and between said angular parts are inserted the heretofore described tie-plates 99, of the device as seen in Fig. 11, the angle plate 97 fitting upon the 95 outer surfaces of the side plates 45 and 60, of the outer and inner compartments, are afforded a closed end wherever they are cut, in order to make the joint with the plates 98.

It will be observed that the lips 59^a, in 100 the upper and lower portions of the plates 45 and 46, 60 and 70, are removed so as to permit the sections to fit between the flanges on the bed and bridging plates. These parts of the sections, in order to give resistance to 105 outward distortion from the weight of the concrete are held together by means of a rod 102, the ends of which are provided with hooks 103, as seen in Fig. 13, and the hook on said ends are made to engage with the 110 apertured portions of the ribs 47, on the respective, opposite parts of the compartments, these rods forming also a reinforcement.

One course of the reinforcement being 115 thus completed, wet concrete is supplied to the compartments of the combined form and reinforcement, in quantity, and a proportionate amount of the concrete flows through the apertures in the plates of the reinforcement and enters the recesses of the studs from opposite compartments or sections and uniting the body of concrete in the adjacent compartments with the body of concrete within the recesses of the studs. This outward flow of concrete is then spread on the outer surfaces of said reinforcement to the proper degree of thickness, and troweled down, thus affording a non-moisture-absorbing 120 surface, both on the exterior surfaces of 125 130

the wall and the hollow spaces between the compartments, the latter being readily finished when the walls are in process of construction.

5 Upon the completion of the first course of the reinforced concrete wall, the bridging 90 is placed in position, the lower portions of the flanges 91 and 92 extending downwardly over a portion of the outer surfaces 10 of the compartments, the connecting portions 95 serving as reinforcement laterally to the compartments, and at the same time preventing distortion of the plates forming the sides to the compartments, the connecting portions or plates 94 are so positioned as to cover the spaces 78, between the portions 74, of the spacing plate 70, which portions form terminals to the hollow spaces in the reinforcement. Upon the bridging 90 20 is then placed the superposed form and reinforcement as first described, mounted on the bed 80, and the compartments thereof supplied with wet concrete, and the walls finished as before described, the operation 25 being continued the height desired.

In the construction of partition walls which form a part of the building wall, as seen in Fig. 1, the compartments of the reinforcement are formed by the assemblage of 30 the entrained main body sections, as seen in Fig. 2, the interlocking parts of the studs at the ends of the main body section telescoping with the centrally located studs of another section, thus forming compartments 35 as seen in Fig. 8. The bed employed in the partition wall consists of a flanged plate 103, as seen in Fig. 9^a, which is provided with apertures 104 and lips 105, similar in manner to the bed shown in Fig. 9. The 40 apertured, flanged plate 100, as seen in Fig. 12, is placed in a vertical position against the combined form and reinforcement for the main walls of the building, the flanges serving to prevent the spreading, or distortion 45 of the cut portions of the plates 45 and 46, of the form. Upon the completion of one course of the partition wall the bridging 106, shown in Fig. 10^a is placed upon the plates 45 and 46 of the reinforcement, 50 and the erection of the partition wall proceeds in like manner as described of the hollow outer walls.

In the assemblage of the combined form and reinforcement, the parts seen in Figs. 55 2, 3 and 4 admit of different combinations than the one shown in Figs. 1 and 5, for the hollow wall construction, such as is shown in Fig. 7. In this arrangement of 30 parts the sections 60 and 70 are alone combined as seen in Figs. 3 and 4, the part 70 being employed in conjunction to form the hollow spaces between compartments in the reinforcement, as clearly seen in the drawing.

65 The construction of the sections may be

modified as seen in Figs. 16 and 17, in which the parts of the same section are parallel in position and form the respective opposite sides 107 and 108, of the compartment. In this construction a single stud 109, is formed 70 intermediate the ends of the plate constituting the section, the ends of the plate being provided with interlocking sectional parts of studs 110 and 111. Assembled in the manner shown in Fig. 17, the sections 75 are reversed in position in respect to each other, and the sectional parts of the studs are fitted telescopically, as in the other sections described. In this Fig. 17, the compartments are formed with a repetition of 80 body sections, as seen in Fig. 16.

A modification of the forms and reinforcement for solid or hollow walls is seen in Fig. 14, in which a single stud 112 is formed intermediate the ends of the plate 85 forming the body-section and equi-distant from the spacing plates 113 and 114. In Fig. 18 the body section as seen in Fig. 14 is combined with the body section as seen in Fig. 16, this arrangement affording the 90 hollow spaces between parallel compartments. Instead of the form of stud as shown in Fig. 1, I may employ the form of stud shown in Figs. 14, 15, 16, 17 and 18, in which the interlocking portions of a stud 95 integral with the offsets 117, 118 are inclined at an angle to the offsets, as at 115 and 116, thereby lessening liability of the interlocking portions of a stud to disengage and become separated in the introduction of 100 the concrete to the compartments.

Instead of the transverse connecting strips 83, in the bed plate as seen in Fig. 9, I may employ a flat strip 120, as seen in Fig. 19, the central portion of which is provided 105 with a rib 121, similar to the ribs 47, in Fig. 2, the rib 121 extending upwardly, and the plate 120 having upwardly-extended flanges 122, this plate 120 being independent of 110 parallel bed plates 123.

For light partitions and walls, a fireproof structure may be obtained in the employment of my reinforcement as a combined studding and plate structure, which plate structure may be covered with plaster or 115 stucco. The side members or plates in such uses may be punched out or perforated but the studs need not be punched out.

The invention is applicable to the erection of all kinds of buildings of concrete, and 120 for bridges, piling and foundation structures, such as curbing, revetments, elevators for storing grain, the advantages of my invention being that the form which serves to support the concrete in setting becomes a 125 permanent reinforcement through which moisture cannot penetrate, and which is susceptible of quick repairs, the lips on the reinforcement serving to bind the exterior wall surfaces of concrete to the reinforce- 130

ment wherever used, and the studs affording the relief from tension stresses which may be set up in concrete walls. I also afford by means of the recesses 40 and 41, in the main body sections a means for engagement for the interlocking part of studs that prevent lateral lines of separation at the junction of the parts of said studs and resist longitudinal strains upon the body sections. The 10 various modes of assembling the body sections with the other allied sections enables the studs to be positioned at points best adapted to resist lateral pressures, such as walls and partitions to buildings, and in 15 the hollow wall construction the continuity of the concrete walls, which as seen are unbroken, the studs are positioned to afford resistance to all tension and cross bending stresses to which the reinforcement may be 20 subjected, or to give the basis for all circuitous passages.

I am aware that sheared portions of two abutting flanged plates have been bent over upon themselves to form the securing element to folded parts of the plates at right angles to the body portion. In my invention the sheared parts are intended to prevent spreading apart of the folded portions of the ribs hence the sheared parts are in 30 vertical alinement with the rib.

I am also aware that corner braces have been employed formed of folded strips of metal bent to form reentrant angles, the wings being separable at one end of the 35 brace. In my invention the folded parts terminate upon the central arm of the brace thus making the parts non-separable.

Such other modifications may be employed as are within the scope of the 40 appended claims.

Having fully described my invention, what I now claim as new and desire to secure by Letters Patent is:

1. In concrete hollow wall construction, 45 a continuity of main parallel reinforcing body sections spaced apart, each section comprising longitudinal plates spaced apart, interlocking distance plates forming an integral part of the adjacent plates of the oppositely alined main body sections, said distance plates extending transversely to each body section and in reverse directions from the main body sections and spaced apart in parallel planes, one spacing plate 50 being connected with the interlocking spacing plate of one body section in parallelism and the other companion spacing plate being connected with the interlocking spacing plates or members of the adjacent body sections in parallelism.

2. In concrete hollow wall construction, 60 a continuity of main parallel reinforcing body sections spaced apart, each section comprising longitudinal plates, spaced apart, 65 interlocking distance plates dividing the

plates in each body section, and forming an integral part thereof, said distance plates being extended laterally and in reverse directions from each body section and spaced apart in parallel planes, said spacing plates 70 being integrally connected with the interlocking plates of adjacent body sections, in parallelism.

3. In concrete hollow wall construction, 75 wall reinforcing plates spaced apart in parallel planes, and transverse interlocking distance members separating the plates into compartments or sections; and a corresponding section or sections of like reinforcement in alinement therewith; portions of opposite 80 inner wall reinforcing plates being bent laterally in parallel planes constituting spacing members between the alined compartments and engaging with the interlocking distance members of the respective opposite alined sections and forming between their inner face surfaces a passage connecting opposite compartments or sections of the alined reinforcement.

4. A reinforcement for concrete structures 90 comprising oppositely positioned studs and an integrally connected distance plate, the ends of which distance plate are bent to form grooves adjacent thereto thence bent outwardly to form recessed studs opening in 95 opposite directions, the outer face portions of each stud terminating in an inward depression or groove.

5. A reinforcement for concrete structures 100 comprising oppositely positioned studs and an integrally connected distance plate, the ends of which distance plate are bent to form grooves adjacent thereto thence bent outwardly to form recessed studs opening in opposite directions, the outer face portions 105 of each stud terminating in an inward depression or groove, and a reinforcement whose grasping end is composed of bent portions extended telescopically upon the outer surfaces of said stud or studs and 110 engaging with the sides of the respective grooves.

6. A reinforcement for concrete structures 115 consisting of a longitudinally extended body plate, a portion of which plate intermediate its ends is bent transversely to form a distance plate, one outer portion of which distance plate is bent to form a recessed portion or stud and grooves in the outer faces thereof, the recess opening in the direction 120 of one end of the body section and the other outer portion of the distance plate bent to form a recessed portion or stud and grooves in the outer face portion thereof, the recess opening in the direction of the opposite end 125 of the body section, the outer ends of the body plate being folded on itself a short distance from the end of the plate, the folded end portions being bent inwardly 130 parallel with the grooves in the outer por-

tions of the studs, the ends of the body plate being thence bent outwardly terminating in a grasping end and of like configuration but of slightly larger cross section than the 5 corresponding outer face portion of the said studs.

7. In a reinforcement for concrete hollow wall construction, superposed sections of longitudinally extended reinforcing plates 10 and interlocking distance plates composing the ends of each section, said sections being arranged horizontally in the wall in parallelism, horizontal apertured bridging plates between the superposed sections and 15 upwardly and downwardly bent sectional flanges thereon, a transverse connecting plate connecting one bridging plate integrally with the bridging plate in parallelism.

8. Reinforcements for concrete walls comprising a continuity of oppositely aligned longitudinally extended main body plates, each main body plate intermediate its ends being bent transversely to form a distance plate, one outer end portion of each distance 25 plate or plates being bent to form a recessed portion or stud and grooves in the outer face portions thereof, the recesses opening in the direction of one end of the body plate, and the other outer portion of each distance 30 plate being bent to form a recessed portion or stud and grooves in the outer faces there-

of, the recess opening in the direction of the opposite end of each body plate, the outer ends of each body plate being folded upon itself a short distance from the ends of 35 the plate, the folded end portion being bent inwardly and the ends of the body plate being thence bent outwardly terminating in a grasping end which with the folded end portion forms an end stud, which end stud 40 is telescopically interlocked with the adjacent stud on the distance member of an adjacent section.

9. Reinforcements for concrete walls comprising body sections or plates in parallel 45 planes, transverse distance members or plates integral with the body sections, the outer end portions of each distance plate being bent to form recessed studs opening in opposite directions, the outer face portion of each stud terminating in an inward depression or groove and the outer ends of each body plate being bent inwardly to form a grasping end, which end is telescopically interlocked within the groove carried by the adjacent stud on the distance member of an adjacent body section. 50 55
